UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed July 29, 1924. Serial No. 728,828.

This invention relates to tally-sheet mechanism, and more particularly to means whereby a tally-sheet may be made an ink-copy instead of a carbon-copy. This invention is an improvement on devices shown in the patent to F. A. Hart, No. 1,281,160, dated October 8, 1918.

In accordance with said patent, in making a duplicate on the tally-sheet of the work 10 done on the original work-sheet, a carbon-sheet is inserted between the tally-sheet and the work-sheet. This carbon-duplicate, however, is unsuitable for many kinds of work, a duplicate made with permanent ink being required.

It is the primary object of the present invention to provide a duplicate typed with permanent ink, the same as the typing on the original work-sheet. This is accomplished 20 by providing a separate inked ribbon positioned next to the tally-sheet. To protect the tally-sheet from being soiled by this auxiliary ribbon, the ribbon is carried on a supply-spool separate from the tally-sheet-supply spool, and is received on a spool separate from the tally-sheet-receiving spool.

The objection to the use of such an auxiliary ribbon behind the work-sheet, because it would mark and print on the reverse side 30 of said sheet, is overcome by inserting a continuous shield or protector, which is in the form of a long web of paper, between the tally-sheet auxiliary ribbon and the original work-sheet. This shield is supplied from 35 and received on separate spools. The auxiliary-ribbon-supply spool and its receiving spool may be used interchangeably, that is, when the supply of ribbon on the supply-spool becomes exhausted, the supply-spool 40 can be removed, and the receiving spool with its supply of ribbon substituted, the empty supply-spool being positioned to receive the ribbon. The supply and receiving spools for the paper shield are also used 45 interchangeably. All of the aforesaid receiving spools are mounted to be driven simultaneously, by the platen line-spacing mechanism, to feed their webs around the platen uniform line-spacing distances and 50 independently of the platen.

Other features and advantages will hereinafter appear.

In the accompany drawings,

Figure 1 is a front view of a typewriter 55 platen and frames with the present invention applied thereto, parts being broken away.

Figure 2 is a sectional view, taken on the plane indicated by the line A—A of Figure 1 and looking in the direction of the 60 arrows.

Figure 3 is a sectional view, taken on the plane indicated by the line B—B of Figure 1 and looking in the direction of the 65 arrows.

Figure 4 is a detail sectional view, showing how the ribbon-receiving spool is mounted.

Figure 5 is a sectional view, taken on the plane indicated by the line C—C of Figure 70 4 and looking in the direction of the arrows.

Figure 6 is a sectional detail view, showing how the ribbon-supply spool is mounted.

The platen 1 is carried by a shaft 2, which 75 is rotatable in the platen-frames 3 and 4. This platen 1 is rotated by a hand-wheel 5 or by a lever 6 acting on a pawl 7 and ratchet-wheel 8, which is fixedly secured to the shaft 2. Securely mounted on the 80 platen-frames 3 and 4 are brackets 9 and 10. These brackets 9 and 10 support a rod 11, on which are mounted intermediate its 85 ends frames 12 and 13. Journaled in said frames 12 and 13, adajacent their top and rear ends and mounted parallel to the platen 1, is a tally-sheet spool 14 for supplying the tally-sheet 15. Immediately forward of said supply-spool 14, in said frames 12 and 13, is journaled, parallel to the platen 90 1, the tally-sheet-receiving spool 16, fastened to which, on the outside of the left-hand frame 12, is a gear 17. The mounting of said supply-spool 14 and receiving spool 16 is the same as the mounting for the auxiliary-ribbon-supply-and-receiving spools, 95 presently to be described.

Instead of using a carbon-sheet to make an impression on the tally-sheet, as is the case in said Patent No. 1,281,160, in the 100 present invention an inked ribbon is used. This is done by mounting rotatably between the frames 12 and 13, and parallel with the platen 1, a spool 18 for supplying an auxiliary ribbon or inking web 19. This 105 spool 18, as shown in Figure 6, is rotatably mounted in the frames 12 and 13 by means of screws 20 and 21, respectively. Knurled knobs 22 and 23 are fastened to said screws 20 and 21, respectively. The free end of the 110

auxiliary ribbon 19 is carried underneath the platen 1, and upwardly to a receiving spool 24. This spool 24 is provided with a slot 25 for receiving the free end of the ribbon 19. This receiving spool 24 is rotatably and detachably mounted in the frames 12 and 13 and parallel to the platen 1 by means of screws 26 and 27. It will be noted that when the supply of ribbon on 10 the supply-spool 18 is exhausted, the spool 18 may be removed from the frames 12 and 13 and the receiving spool 24 substituted in its place, the empty supply-spool 18 being mounted to receive the ribbon. Carried on 15 the left-hand screw 26, and outside of the frame 12, is a gear 28, the hub 29 of which passes through the frame 12 and into the spool 24. This hub 29 is squared, as indicated at 30, to prevent relative rotation 20 between the gear 28 and the spool 24. The gear 28 is in mesh with the gear 17. The presence of this inked auxiliary ribbon 19 next to the tally-sheet 15 results in said tally-sheet 15 being typed with the ink on 25 ribbon 19. With such an inked ribbon 19 between the tally-sheet 15 and the original work-sheet 31, ordinarily, the reverse side of the work-sheet 31 would receive offset typed impressions. To take care of this, 30 in the present invention, a protecting shield 32 in the form of a web of paper is inserted between the auxiliary ribbon 19 and the work-sheet 31. This protecting web 32 is supplied from a spool 33 mounted in the 35 frames 12 and 13, parallel to the platen 1, and is received by a spool 34 mounted in said frames 12 and 13 parallel to the platen. The mounting of these spools 33 and 34 is the same as the mounting for the spools 18 and 24 for the ribbon 19. The receiving 40 spool 34 has a gear 35 removably mounted in its left-hand end, which gear 35 meshes with the gear 28. It will be noted that the gears 17, 28 and 35 are in mesh.

45 Supported rotatably by the brackets 8 and 9 and passing through the frames 12 and 13 is a drive shaft 36. This shaft 36 has keyed thereon at a point outside the frame 12 a gear 37. This gear 37 meshes 50 with the gear 35 of the shield-receiving spool 34. At the left-hand end of this shaft 36 is fixedly mounted a ratchet-wheel 38. This ratchet-wheel 38 is driven by a pawl 39 which is actuated by a link 40 connected 55 to the lever 6 by a slide 41. The pawl 39 is held in engagement with the ratchet-wheel 38 by means of a spring 42, and the ratchet 38 is held by a spring-detent 43.

60 In operation, when the lever 6 is pulled to advance the platen 1, the shaft 36, through the pawl-and-ratchet mechanism described, is driven simultaneously. This shaft 36 drives the gear 37, which, in turn, drives the gears 35, 28 and 17, thus winding each 65 one of the spools on which these latter gears

are mounted. As will be noted, when the type 44 strikes the main machine ribbon 45, the character on the type 44 is impressed on the work-sheet 31 with permanent ink, and, by reason of the presence of the second 70 ink-ribbon 19 next to the tally-sheet 15, said tally-sheet has also impressed thereon the same character with permanent ink. The protecting web 32, positioned between the work-sheet 31 and the auxiliary ribbon 19, 75 prevents typing on the reverse side of said work-sheet.

At Figure 1 it will be noted that the work-sheet 31 is considerably wider than the tally-web, which provides work-sheet 80 areas at each side edge of the tally-web, and the usual Underwood feed-rolls of the platen are spaced to straddle the tally-web position and only bear upon these two side edges of the work-sheet. This arrangement 85 provides that the outer work-sheet may have variable standard line-spacing movements predetermined by the setting of the line-spacing mechanism, and that the tally-web and its ribbon and protective web may be 90 fed differentially to the line-spacing movement of the platen and the work-sheet, for uniform condensed spacing of the tally-web.

It will be further noted that the feeding 95 of the auxiliary ribbon, tally and protective webs around the platen in unison as a unit prevents the inked fabric from smudging or otherwise soiling the face of the tally-web, as is usually the case when the tally-web is drawn under a stationary inking 100 element or across a transversely fed inked ribbon, as heretofore; and that by cutting the tally-web, ribbon-web and protective paper-web in uniform lengths, the reversal 105 of the ribbon and paper web-spools may take place at the same time that a new tally-web is supplied to the platen.

Variations may be resorted to within the scope of the invention, and portions of the improvements may be used without others. 110

Having thus described my invention, I claim:

1. In a typewriting machine, the combination of a platen arranged to feed a work-sheet, tally-recording mechanism including individual means for drawing a tally-web, an inking web and a protective web around the platen, and line-spacing mechanism operative to line-space the platen and operatively connected to the tally mechanism to 115 simultaneously effect a joint line-spacing movement of all the webs.

2. In a typewriting machine, the combination of a platen arranged to carry a work-sheet, tally-recording mechanism including a spool for the tally-web, a spool for the inking web and a spool for the protective web, line-spacing mechanism to line-space the platen and the work-sheet, and gear-driven means actuated by the line-spacing 125 130

- mechanism and connected in train to drive the spools of the webs simultaneously to effect a joint line-spacing movement of the webs.
5. 3. In a typewriting machine, the combination with a rotatable platen for holding a work-sheet, of a tally-web supply spool from which a web is delivered around the platen, a main ribbon for printing on said work-sheet with permanent ink, a tally-web-receiving spool, a supply-spool for delivering an auxiliary ribbon around said platen for manifolding on said web with permanent ink, a separate receiving spool 10 for said auxiliary ribbon, a supply-spool for delivering a protective web between said auxiliary ribbon and work-sheet, a separate receiving spool for said protective web, and means for rotating said receiving spools as a unit and independently of said platen.
15. 4. In a typewriting machine, the combination of a platen arranged to feed a work-sheet, tally-recording mechanism including a spool for a tally-web, a spool for an inking web and a spool for a protective web, line-spacing mechanism to line-space the platen and the work-sheet a predetermined extent, and gear-driven means actuated by the line-spacing mechanism and operatively connected in train with the spools of the three webs to simultaneously effect a unitary line-spacing movement of the webs of lesser extent.
20. 5. In a typewriting machine, the combination with a rotatable platen for holding a work-sheet, of a tally-sheet-supply spool from which a strip is delivered around the platen, a main ribbon for printing on said work-sheet with permanent ink, a tally-sheet-receiving spool, a gear mounted on said receiving spool, a supply-spool for delivering an auxiliary ribbon around said platen for printing on said strip with permanent ink, a separate receiving spool for 25 said auxiliary ribbon, a gear mounted on said receiving spool, a supply-spool for delivering a shield between said auxiliary ribbon and work-sheet, a separate receiving spool for said shield, a gear mounted on said shield-receiving spool, all of the afore- 30
- said gears being in mesh, a drive shaft mounted parallel with said platen, line-space mechanism for rotating said platen, a train of gears between said line-space mechanism and said drive shaft, and a gear on 35 said drive shaft meshing with the gears on the receiving spools to drive the latter.
6. In a typewriting machine, the combination of a platen including a line-spacing mechanism to line-space the platen and a work-sheet, a spool operable to feed a tally-web around the platen to underlie the work-sheet, a spool operable to feed an inking web around the platen to overlie the tally-web, a spool operable to feed a protective web around the platen to overlie the inking web to prevent offsetting of the inking web to the adjacent face of the work-sheet, and means operatively connecting the line-spacing mechanism to the three spools whereby 40 the feeding movement of the spools will vary from the feeding movement of the platen.
7. In a typewriting machine, the combination of a platen including a line-space mechanism to line-space a work-sheet with the platen, tally-mechanism including individual feeding means for a tally-web, an inking web and a protective web arranged in superposed relation around the platen, 45 and means actuated by the line-space mechanism in line-spacing the platen and operatively connected to drive said individual feeding means to line-space the three webs as a unit independently of the platen.
8. In a typewriting machine, the combination of a platen including a line-spacing mechanism to line-space the platen and a work-sheet, tally-mechanisms including a tally-web spool, an inking web spool and a protective web spool to be individually rotated to draw their webs around the platen and under the work-sheet in superposed relation, and means co-operative with the line-spacing mechanism and connected to rotate 50 the spools to line-space all the webs in unison through a condensed line-space distance.

JESSE A. B. SMITH
